UNITED STATES PATENT OFFICE.

AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SUBMARINE SIGNALING.

Application filed August 28, 1924. Serial No. 734,581.

This invention relates to submarine signaling system and more particularly to receiving equipment for such a system.

It has for its principal object the correction of the distortion of signals transmitted over a long submarine cable and their amplification to a value suitable for the operation of a receiving instruments.

Another object is to terminate a cable which is grounded through a high impedance, in such a manner as to efficiently receive signals. In the accomplishment of this object a receiving system is provided, the impedance of which viewed from the cable is at least several times as high as the cable impedance at all frequencies essential to signaling, and at low frequencies it is many times as high as the characteristic impedance of the cable.

Another object is to terminate a loaded cable in such a manner as to prevent hysteresis distortion due to the building up to an abnormally high value of low frequency current components. This is accomplished by providing a high impedance termination for the cable for the low frequency components of the signal, which insures that a long succession of signals, wherein one polarity predominates, does not cause the current at the receiving terminal of the cable to build up to an abnormally high value. This is of great importance in the operation of cables loaded with a nickel-iron or other alloy having a high permeability at low magnetizing forces, since the "pile-up" of current of one polarity makes the cable operate in a partially magnetized condition and causes hysteresis distortion of the received signal.

Another object is to terminate a cable balanced by a terminal arrangement having a high impedance ground connection so as to obtain a high ratio of signal strength to out of balance interference. This is accomplished by providing a high impedance termination for the cable for component frequencies in the neighborhood of the signaling frequency. This insures that the ratio of signaling to out of balance interference is as favorable as possible. The terminal arrangement having a high impedance ground connection comprises a partial

return circuit terminated at sea including a long metallic conductor and a network preferably located at the sea termination, the entire return circuit forming a balance for the cable. The advantages of such an arrangement are fully explained in a copending application of J. J. Gilbert, Serial No. 734,580, filed Aug. 28, 1924.

Another object is to make possible the efficient use of a grounded amplifier in combination with a cable balanced by a terminal arrangement having a high impedance ground connection. Such terminal arrangement also preferably comprises a partial return circuit terminated at sea including a long metallic conductor and a network preferably located adjacent to the sea terminal, the entire return circuit forming a balance for the cable. The main cable and this terminal arrangement are inductively associated with the grounded amplifier. This insures the maintenance of the balance between the main cable and the terminal arrangement with respect to interference.

In the embodiment of this invention chosen for illustration all of these objects are simultaneously accomplished. In this embodiment a single core submarine cable loaded with a nickel-iron alloy is terminated in a twin core section, each conductor of which is similarly loaded. At the sea end of the twin core section, one conductor is spliced to the single core cable and the other is grounded through a substantially pure resistance having a value approximately equal to the characteristic impedance of the single core cable. At the shore end, the twin core section is terminated in a network consisting of a shunted condenser in series with a shunted inductance and a resistance all so proportioned that when coupled to a receiving electron discharge amplifier by means of a transformer having a very high ratio of inductance to resistance the network performs the four functions hereinbefore defined.

The novel features which are considered characteristic of this invention are set forth with particularity in the appended claims. The invention, both as to its organization and method of operation together with other objects and advantages thereof, will be fur-

ther explained hereinafter having reference to the accompanying drawing.

Fig. 1 of the drawing shows diagrammatically the preferred embodiment of the invention as hereinbefore described.

Fig. 2 illustrates schematically a type of receiving amplifier suitable for use in the system of Fig. 1.

Fig. 3 shows modifications of the arrangement of Fig. 2.

Figs. 4, 5 and 6 illustrate the preferred type of transformer construction.

Fig. 7 illustrates a section of loaded conductor.

Referring now to Fig. 1 of the drawing, a single core submarine cable 5 is terminated in a twin core section of submarine cable 6 which extends between the lines W—W and X—X. One core 7 of the twin core section 6 is spliced at one end to the single core cable 5 and at the other end is connected to a switch 8 by means of which it can be connected in its upper position to the signal re-

ceiving apparatus "R" and in its lower position to the transmitting apparatus "T". The other core 9 of the twin core section is connected at the sea end through a resistance 10 to a conductor in contact with the sea water. In the particular arrangement shown, the resistance is connected to the cable armor wires at point 13 and a conventional ground connection shown by dotted lines is used to indicate that the armor wires are ground d. The core 9 together with the network 10 grounded at the point 13 constitute a cable balancing return circuit. The shore end of core 9 is connected to the receiving apparatus "R".

A type of core suitable for both the single core cable and the twin core section is illustrated in Fig. 7. This core comprises a copper cond. 11 or 14 provided with a wrapping 15 of a nickel-iron alloy as described and claimed in a copending application of G. W. Elmen, Serial No. 557,928, filed May 2, 1922. The advantage of using this loading material is that its permeability at small magnetizing forces of the order of 0.01 to 0.10 gauss is from 10 to 20 times that of iron, that is, from 2000 to 4000. Over the wrapping of nickel-iron alloy, an insulating layer 16 of gutta percha or similar material is applied. The cable on which the receiving apparatus herein described is intended to operate, when protected by armor wires in accordance with the standard submarine cable practice, has a characteristic impedance which is approximately a resistance of 400 ohms in the range of signaling frequencies.

The reason for employing a cable balancing return circuit is that interfering disturbances local to the shore end of a submarine cable are reduced thereby. Such a sea earth arrangement is described and

claimed in a copending application of J. J. Gilbert, Serial No. 648,690, filed June 30, 1923.

The transmitting equipment "T" comprises a well-known positive and negative impulse transmitter 17, series resistance 18 and condenser 19, with shunting resistance 20. As hereinbefore explained, the transmitting equipment "T" may be connected to the core 7 of the twin core section 6 by means of switch 8 in its lower position. Similar transmitting equipment (not shown) is provided at the distant end of the cable 5 for transmitting to the receiving apparatus "R" and need not be further described.

The immediate termination for the twin core section 6 consists of a condenser 21 in series with an inductance 22. Resistance 23 connected in shunt of condenser 21; resistance 24, in shunt of inductance 22; and resistance 25, in series with inductance 22 are provided for the purpose of preventing free oscillations, and for the control of the low frequency components of signaling current as will be further described hereinafter. Shielded transformer 26 is used to couple the inductance 22 to a receiving amplifier "A". The secondary winding 27 of transformer 26 is surrounded by a shield 28 which is connected to the locally grounded terminal of winding 27.

The amplifier "A" may be of any suitable design and preferably employs electron discharge amplifying devices as indicated. The output circuit of amplifier "A" extends through a receiving device 29 which may be a siphon recorder as indicated. In the arrangement shown the indicating device 29 is located at a considerable distance from the amplifier "A" and is connected thereto by means of a cable 30. A second indicating device 31, which may also be a siphon recorder as shown, is connected in series with the output circuit adjacent to the amplifier "A" for monitoring purposes.

As hereinbefore mentioned, a cable balancing return circuit for the cable 5 is provided in order to prevent interference due to local fields. The effectiveness of such an arrangement depends upon the conductors 7 and 9 having equal impedances to earth and it is therefore obvious that an unbalance to earth of the shore end of the conductors will increase the amount of interference received. It is necessary to ground the filaments of the amplifier locally at the cable terminal through an earthing or stabilizing path of sufficiently low impedance to prevent the amplifier from oscillating, as indicated by the conventional earthing symbol at the amplifier filaments in Fig. 1. Therefore, in order to avoid unbalancing the main cable and the cable balancing return circuit with respect to earth it is necessary to couple the amplifier "A" to the ter-

minating network by means of the transformer 26.

Since it is possible to maintain a high signaling speed on the loaded cable 5, the transformer 26 must be capable of faithfully transmitting a wide range of frequency components. For signaling speeds of 60 cycles per second or less, it is desirable that the transformer, when combined with proper shaping networks be able to maintain a nearly constant secondary potential for about a second, if the potential at the sending end of the cable is held steady through some combination of signals. In order to reproduce the signals accurately it must pass frequencies about 1.5 times the signaling frequency without distortion. In other words, the transformer must operate efficiently over a range of frequencies from approximately one-tenth to 100 cycles per second. In order to obtain the largest possible signal response, when using the cable balancing return circuit, the network terminating the cable and return circuit must have an impedance which is at all frequencies essential to signaling considerably higher than 800 hms, which is approximately the impedance between the cable and the return circuit. A high impedance arrangement for this purpose is disclosed and claimed in the copending application of J. J. Gilbert, Serial No. 734,580, supra. In order to prevent the building up of large amplitudes of very low frequency current at the receiving end of the cable, and thus to minimize a troublesome form of hysteresis distortion, the network must also have as high an impedance as possible for the low frequencies. This is a feature of the present invention.

It has been found that by suitably designing the elements of the network and transformer 26, these requirements can be met. It has also been found that a transformer having a primary inductance of several thousand henrys and an effective resistance of the order of one half ohm per henry at the very low frequencies is suitable. In order to obtain such a transformer, it is necessary to use for the magnetic core, a nickel-iron alloy which has high permeability at low magnetizing forces.

A suitable type of transformer is illustrated in Figs. 4, 5 and 6. The core is of the "shell transformer" type and is made up of strips of nickel-iron alloy, which strips are all of uniform width and thickness, namely 1.7 inches wide and 6 mils (0.006 of an inch) thick. This material as received from the mill is rolled up in spiral form. In order to remove the resulting curl, it is first annealed and then stretched about one-half of one per cent. The core is made up of pieces of two different lengths, namely 7 inches and 8.7 inches. After the stretched mate-

rial is cut into length it is annealed by slowly cooling from a temperature of 1000° centigrade. The center limb 50 of the transformer which carries the windings, is made up as nearly as possible of solid metal, 70 while the outer limbs 51 to 54, inclusive, have only one-half as much material except where they overlap each other and the center limb, thus making the combined area of the cross section of the two outer limbs equal to that 75 of the center limb 50.

The arrangement of the strips is shown diagrammatically in Fig. 6 which shows the assembled core as viewed from the lower end of Fig. 5. Their arrangement is also shown in Fig. 4 which is a cross-section of Fig. 5 looking down at a point just above the shield surrounding the secondary winding. It is to be understood that Figs. 4, 5 and 6 are not drawn to scale. 80 85

Although there are four joints in the magnetic circuit, with this type of core construction their effect is largely reduced by the large areas in contact at the corner and at one end of the center limb laminations and by staggering the joints at the short end of the center limb. One side of the lamination of the center limb is lacquered for the purpose of reducing eddy currents. The completed core is held together by wooden 90 95 clamps and brass screws. From measurements made of the inductance of the completed coil, the permeability of the core at low flux densities was found to be about 3000. 100

Unless the transformer 26 has the windings designed to reduce distributed capacity to a minimum, it is likely to cause signal distortion by resonance between its leakage reactance and its distributed capacity at 105 some high frequency component of the signaling current. It is also essential that the windings contain no short circuited turns. For these reasons, the coils are wound on an arbor in the form of pancakes one quarter of an inch thick. The coils in position on the arbor are suitably impregnated, for example, by soaking in a wax impregnating compound at 120° centigrade for several 110 hours. 115

The primary winding consists of sixteen pancake sections arranged in groups of fours. These are indicated by groups 54 to 57 inclusive. The sections in each group are separated by 0.01 inch red rope paper and bound together with silk ribbon. The primary sections each contain 1300 turns of No. 30 single silk covered copper wire and have a resistance of about 110 ohms. The sections in each group are connected in series and two terminals brought out. Means are provided for connecting the groups in various combinations as desired. 120 125

The secondary winding 58 consists of three sections, each of 7200 turns of No. 40 130

single silk covered copper wire having a resistance of 6700 ohms. The sections are separated from each other by 0.02 inch red rope paper and protected at the ends by 5 1/32 inch of cardboard. A split shield 59 of one mil (0.001 of an inch) copper is built up around the group of sections and the whole wrapped closely with silk ribbon. The group of secondary coils is assembled 10 in the center of the core as shown with two groups of primary sections on each side of it. Two terminals are brought out from each secondary pancake and external means are provided for connecting the pancakes 15 in any desired combinations.

By far the larger part of the winding space is occupied by the primary coil, only sufficient space being occupied by the secondary coil to give a reasonable primary to 20 secondary turns ratio when the smallest wire available is used for the secondary winding. The use of a high resistance secondary coil is permissible on account of the fact that the secondary coil works into practically 25 an infinite impedance.

Measurements on the transformer described at a value of current of the order of that encountered in submarine signaling show that its primary inductance is 6300 30 henrys and its direct current resistance is about 0.28 ohms per henry. With the primary winding closed on its normal impedance, the leakage inductance measured from the secondary terminals is of the order of 35 50 henrys. The ratio of primary reactance to primary resistance is not less than 50 from 4 to 20 cycles per second. The capacity between the primary sections adjacent to the secondary shield and the shield is of the 40 order of 500 micro-micro-farads.

The function of the shaping network will now be considered. The current arriving at the receiving end of a submarine telegraph cable, contains signaling current components 45 from nearly zero up to a frequency several times that of the normal signaling frequency, but with the lower frequency components very much stronger than the higher frequency components and with the high frequency components preceding the low in time 50 of arrival. In order to restore the signal to a recognizable form, it is necessary to make the conditions for reception as favorable as possible for the frequency components of the 55 order of 1.5 times the signaling frequency and proportionally less favorable for higher and lower frequency components and at the same time to correct the phase displacements and avoid oscillations in any resonant circuits which may be used. In the present 60 arrangement, it is also necessary to keep the terminal impedance high at all frequencies essential to signaling and particularly high at the lower frequencies in order to minimize 65 hysteresis distortion.

These requirements are met in the network which joins the cable to the amplifier, by the combination of a condenser and an inductance in series, of such values that their reactances are approximately equal at 1.5 70 times the signaling frequency. Oscillations are avoided by the shunt resistance 24 connected across inductance 22, a proper amount of very low frequency components of the signal are allowed to pass around condenser 75 21 by way of the high resistance shunt 23, and the ratio of resistance to reactance over the circuit of coil 22 is adjusted to the proper value by resistance 25. The voltage across the inductance coil 22 and its associated resistances 24 and 25 is then impressed on the primary winding of transformer 26 and through it upon the input of the amplifier "A". The minimum impedance of the 80 network is then at approximately the resonant frequency of the inductance 22 and the condenser 21, and reduces to the effective resistance of these circuits. This arrangement permits the terminal impedance to be raised indefinitely by raising the inductance 85 and correspondingly reducing the capacity. Practical questions of design, however, have so far limited the inductance to about 50 henrys. The interposition of a shielded transformer 26, such as described hereinbefore, in connection with Figs. 4 to 6 inclusive, between the inductance 22 and the input circuit of the amplifier "A" modifies 90 the operation of the circuit only slightly.

If the primary reactance of a transformer 100 is large compared to the resistance of its circuit, the current through the primary windings is directly proportional to the potential and inversely proportional to the frequency of any signal component impressed upon it. Since the secondary potential is directly proportional to the rate of change of the primary current, the secondary potential is of the same form as the primary potential over the range of frequencies for which the primary circuit resistance is low compared to the primary reactance. This may be expressed in another way by saying that the primary current is 105 the integral of the primary potential, while the secondary potential is the derivative of the primary current.

No matter how large the primary reactance is made with respect to the resistance, it is impossible to maintain a steady potential across the secondary of the transformer, if the primary potential is maintained constant. The secondary potential will gradually fall to zero. It is possible however, to maintain a constant secondary potential for an appreciable time, if we permit the primary potential to continue to rise at the correct rate to compensate the tendency of the secondary potential to fall. It is possible to do this by taking advantage of the 110 115 120 125 130

fact that the voltage at the receiving end of a submarine cable continues to rise for several seconds after the voltage is applied to the sending end and making adjustments of the receiving network accordingly. By this means the system of shaping network and transformer of Fig. 1, can be made to act substantially as if there were no transformer for as long as one second.

It is obvious that the adjustments of the elements of the network between the cable and the amplifier depend not only upon the characteristics of the cable, but also upon the speed of signaling and upon the adjustments of any shaping elements which may be included in the amplifier itself. The shaping elements are therefore made adjustable. Condenser 21 has a capacity of 0.01 to ten microfarads, and the shunting resistance 23, a maximum value of two megohms. Inductance coil 22 is variable in steps from about one half henry up to 53 henrys. Resistance 24 has a maximum value of 100,000 ohms and resistance 25, of 10,000 ohms.

A suitable design for amplifier "A" between the lines Y-Y and Z-Z of Fig. 1 is shown in Fig. 2. This amplifier comprises four stages of electron discharge amplifiers with suitable coupling circuits and signal shaping networks. The first amplifier 2A¹ is provided with a negative grid battery 100 of three volts. The filaments of all of the amplifiers are grounded as shown in Fig. 1 and heated by current from a six volt battery under the control of rheostats as shown in Fig. 2.

The output circuit of amplifier 2A¹ is coupled to the shaping network 101 by means of resistance 102 of 200,000 ohms and condenser 103 of 40 microfarads capacity. In series with resistance 102 is space current supply battery 2B¹ of 250 volts. The shaping network 101 consists of primary variable condenser 104 of 0.01 to 0.20 microfarads capacity, secondary variable condenser 107 of 1,000 micro-microfarads maximum capacity, adjustable resistance 105 of a maximum value of 300,000 ohms, and inductance coil 106 of 10,000 henrys maximum inductance and a copper resistance of 45,000 ohms. The design features of a suitable coil are set forth in a copending application of A. M. Curtis Serial No. 690,709, filed February 5, 1924. The upper terminal of coil 106 is connected to the grid of amplifier 2A¹ through a negative grid battery 108 of three volts.

The shaping network 101 is not primarily a resonant network, but comprises an auto-transformer with an abnormally high primary resistance. This resistance is so high in relation to the primary reactance at all of the high frequency components of the signal, that the current in the primary circuit is practically in phase with the voltage across it. However, the turns ratio of the transformer is so large that the secondary induced voltage for the higher frequency components of the signal adds considerably to the voltage transmitted conductively to the secondary terminals by the drop in potential across the primary resistance. The resulting characteristic of this network 101 is that lower frequencies are transmitted to the secondary terminals unchanged, while higher frequencies have their voltage increased substantially. The phase of the components of the signal are shifted approximately proportionately to their frequency. Under these circumstances the phase shifts do not change the shape of the signal, but merely retard it bodily in time but as the amplification is greater for the higher frequencies than for the lower, the attenuation of the cable is partly compensated for. The primary condenser 104 and the secondary condenser 107 are used with caution principally for the purpose of reducing the effect of interference higher in frequency than any of the essential components of the signal and also for introducing any desired phase shift in the signal.

Amplifier 2A² is coupled to shaping network 109 by means of resistance 110 of 200,000 ohms and condenser 111 of 6 microfarads capacity. In series with resistance 110 is space current battery 2B² of 250 volts. Shaping network 109 comprises inductance coil 112 and condenser 113 connected in series across the signaling current output circuit of amplifier 2A². The input circuit of amplifier 2A³ including negative polarizing battery 116 of 4.5 volts, is connected across the condenser 113 which itself is shunted by grid leak resistance 115 of two megohms. Coil 112 has a maximum inductance of 100 henrys and is shunted by resistance 114 variable to a maximum of 200,000 ohms. Condenser 113 has a capacity of 0.01 to 0.2 microfarads.

Amplifier 2A³ is coupled to shaping network 120 by means of resistance 117 of 200,000 ohms and condenser 118 of 6 microfarads capacity. In series with resistance 117 is space current battery 2B³ of 250 volts. The shaping network 120 comprises inductance coil 121 and condenser 123 connected in series across the signaling current output circuit of amplifier 2A³. The input circuit of amplifier 2A⁴ including the negative polarizing battery 125 of 40 volts is connected across the condenser 123 which is itself shunted by grid leak resistance 124 of two megohms. Coil 121 has a maximum inductance of 100 henrys and is shunted by resistance 122 having a maximum value of 300,000 ohms. Condenser 123 is adjustable to a maximum of 0.2 microfarad. Space current for amplifier 2A⁴ is supplied by battery 2B⁴ of 250 volts. Amplifier 2A⁴ consists prefer-

ably of two vacuum tubes connected in parallel. For simplicity one only is shown.

Commercial vacuum tubes manufactured by Western Electric Company, Incorporated, are suitable for the amplifiers. Those designated as No. 102-D are preferable for amplifiers 2A¹, 2A² and 2A³; and those designated as No. 104-D for amplifiers 2A⁴.

The networks 109 and 120 are so adjusted 10 as to reduce interfering currents of frequencies higher than those essential to signaling. The method of adjusting the shaping networks in the amplifier of Fig. 2 is fully explained in the copending application 15 of A. M. Curtis, Serial No. 690,709, supra.

A modification of the amplifier of Fig. 2 is shown in Fig. 3. Identical elements in the two figures are indicated by the same reference characters. The modifications are principally for the purpose of increasing the 20 flexibility of adjustments and in this way permitting the amplifier to operate well over a larger range of signaling speeds than the amplifier of Fig. 2.

25 In the amplifier of Fig. 3 coupling resistances 102, 110 and 117 are each adjustable in four steps up to a maximum of 192,000 ohms. The lower values are used for operation at the lower signaling speeds, to reduce the 30 amount of amplification. Condenser 103 is adjustable from 10 to 40 microfarads capacity. Condensers 111 and 118 each have a capacity of 10 microfarads. Resistance 105 is adjustable up to a maximum of 250,000 35 ohms.

The arrangement of the interstage networks 109 and 120 have been modified in Fig. 3. A potentiometer 130 of network 109 has been substituted for resistance 115 and 40 its location changed to a position where it is in shunt of both coil 112 and condenser 113, instead of in shunt of condenser 113 alone. Similarly resistance 131 of network 120 has been substituted for resistance 124 and has been connected in shunt of both coil 45 121 and condenser 123, instead of in shunt of condenser 123 alone. Potentiometer 130 has a maximum resistance of two megohms, while resistance 121 has a value of two 50 megohms.

55 Networks 109 and 120 may be adjusted so as to consist of a resistance and capacity in series, or an inductance and capacity in series, or a shunted inductance in series with a capacity, the voltage which is impressed upon the input circuit of the succeeding amplifier being that across the condenser in all cases. Each of the adjustments discriminates against interfering components having 60 frequencies higher than those essential to signaling. In addition the first adjustment produces a relative advance in phase of the higher frequency components of the signal with respect to the lower, that is, a 65 shift in the same direction as that produced

by the cable. The second adjustment may be such as to relatively retard the phases of the components up to a certain frequency and advance them beyond that frequency. The third adjustment may be such as to act 70 in either manner depending upon the relative magnitudes of the three circuit elements. These adjustments with respect to network 109 will not be effective unless the potentiometer 130 is set at its maximum point. 75

One method of effecting these adjustments for the purpose of reducing interference, higher in frequency than the signal, is to set the inductances to a maximum and the resistances to infinity, then increase the capacity 80 until an oscillation just commences to be superposed upon the signal. The resistance is then reduced until the oscillation disappears. When networks 109 and 120 are used, the signal shape is somewhat rounder 85 than when they are not used, but interference is greatly reduced. On long loaded cables it may be necessary to use these networks for the correction of phase displacements. 90

The grid polarizing batteries 100, 108, 116 and 125 of Fig. 3 are connected adjacent to the grounded sides of the filaments instead of adjacent to the grids as in Fig. 2. This arrangement simplifies the problem of their 95 insulation.

As hereinbefore pointed out any specific set of adjustments is dependent upon a large number of conditions. As an illustration of about what adjustments might be required 100 for operating at a signaling speed of 56 cycles per second over a loaded cable 2,400 miles long equipped with a balanced sea earth section 100 miles long at the receiving end, the following values for the variable 105 elements are given: Sending condenser 19, 33 microfarads; shunting resistance 20, 11,000 ohms; sending resistance 18, 20 ohms; sending potential, 48 volts; sent signal 110 100% marking.

At the receiving terminal: Condenser 21, 0.16 microfarad; resistance 23, 1,100,000 ohms; inductance 22, 26.5 henrys; resistance of inductance 22, 253 ohms; shunting resistance 24, 40,000 ohms; resistance 25, 3,000 ohms; interstage coupling resistances 102, 110 and 117 each, 192,000 ohms.

Network 101 of Fig. 3: Primary condenser 104, 0.01 microfarad; primary inductance of transformer 106, 200 henrys; primary resistance of transformer 106 and resistance 105, 200,000 ohms; total inductance of transformer 106, 10,000 henrys; secondary condenser 107, 100 micro-microfarads. 120

Network 109 of Fig. 3: Potentiometer 130 (tap at maximum), 2 megohms; inductance 112, 100 henrys; resistance 114, 200,000 ohms; condenser 113, 0.03 microfarad. 125

Network 120 of Fig. 3: Resistance 131 (not adjustable), 2 megohms; inductance 130 130

121, 100 henrys; resistance 122, 200,000 ohms; condenser 123, 0.02 microfarad.

From the values given in the above table for the inductance and resistance of element 5 22 it will be apparent that magnetic material is employed in its magnetic circuit (not shown).

The specific arrangements hereinbefore described are capable of operating at signaling speeds up to 60 cycles per second between 10 New York and the Azores over a submarine cable loaded with nickel-iron alloy. A novel terminal arrangement is employed, which is adjusted to perform a plurality of functions 15 very effectively.

The invention is not limited to the specific arrangements and values hereinbefore given but is capable of considerable modification within the scope of the invention as defined 20 by the appended claims.

What is claimed is:—

1. In a submarine signaling system, a submarine cable, a receiving circuit comprising an inductive shunt connected between said 25 cable and ground, said inductive shunt having magnetic material in its magnetic circuit, a signal indicating device associated with said inductive shunt, and means to make the impedance of said receiving apparatus 30 as viewed from said cable substantially higher for the component frequencies below the signaling frequency than for those above the signaling frequency.

2. In a submarine signaling system, a submarine cable, a receiving circuit comprising an inductive shunt connected between said cable and ground, said inductive shunt having magnetic material in its magnetic circuit, a signal indicating device connected to 40 receive the voltage drop in at least a part of the inductance of said inductive shunt, and a condenser connected in series between said cable and said inductive shunt, the relative impedances of said condenser, magnetic 45 shunt and indicating device being such that the impedance of said receiving apparatus as viewed from said cable is substantially higher for the component frequencies below the signaling frequency than for those above the signaling frequency.

3. In a submarine signaling system, a submarine cable loaded with magnetic material, signal receiving apparatus connected to said cable, and means to make the impedance of 55 said receiving apparatus as viewed from said cable substantially higher for the component frequencies of the signaling current below the signaling frequency than for those above the signaling frequency.

4. In a submarine signaling system, a submarine cable loaded with magnetic material, signal receiving apparatus connected to said cable, and a condenser connected in series between said cable and said receiving 60 apparatus, the relative impedances of said

condenser and said receiving apparatus being such that the impedance of said receiving network as viewed from said cable is substantially higher for the component frequencies below the signaling frequency than 70 for those above the signaling frequency.

5. In a submarine signaling system, a submarine cable loaded with magnetic material, a receiving circuit comprising an inductive shunt connected between said cable and 75 ground, said inductive shunt having magnetic material in its magnetic circuit and a signal indicating device associated with said inductive shunt, and means to make the impedance of said receiving apparatus as 80 viewed from said cable substantially higher for the component frequencies below the signaling frequency than for those above the signaling frequency.

6. In a submarine signaling system, a submarine cable loaded with a nickel-iron alloy, a receiving circuit comprising an inductive shunt having magnetic material in its magnetic circuit and a signal indicating device associated with said inductive shunt, and 85 means to make the impedance of said receiving apparatus as viewed from said cable substantially higher for the component frequencies below the signaling frequency than for those above the signaling frequency. 95

7. A submarine signaling system, a submarine cable loaded with a nickel-iron alloy having a characteristic impedance of about 400 ohms for the signaling frequency, a receiving circuit having an impedance for signaling and higher essential frequency components of at least 2000 ohms. 100

8. In a submarine signaling system, a submarine cable loaded with a nickel-iron alloy and having a characteristic impedance of 105 about 400 ohms in the range of frequencies essential for signaling, a receiving circuit comprising an inductive shunt connected between said cable and ground, said inductive shunt having magnetic material in its magnetic circuit, a signal indicating device connected to receive the voltage drop in at least a part of the inductance 110 of said inductive shunt and a condenser connected in series between said cable and said inductive shunt, the relative impedance of 115 said condenser, magnetic shunt and indicating device being such that the impedance of said receiving apparatus as viewed from said cable is at least 2000 ohms for all the component frequencies essential to signaling. 120

9. In a submarine signaling system, a submarine cable, a receiving circuit comprising an inductive shunt connected between said cable and ground, said inductive shunt having magnetic material in its magnetic circuit, an electron discharge amplifier, a transformer connecting said amplifier to receive the voltage drop in at least a part of the inductance of said inductive shunt, and means 125 130

to make the impedance of said receiving apparatus as viewed from said cable substantially higher for the component frequencies below the signaling frequency than for those above the signaling frequency.

10. In a submarine signaling system, a submarine cable loaded with magnetic material, a receiving circuit comprising an inductive shunt connected between said cable and ground, said inductive shunt having magnetic material in its magnetic circuit, an electron discharge amplifier, a transformer coupling said amplifier to said shunt, and means to make the impedance of said receiving apparatus as viewed from said cable substantially higher for the component frequencies below the signaling frequency than for those above the signaling frequency.

11. In a submarine signaling system, a submarine cable loaded with nickel-iron alloy, a receiving circuit comprising an inductive shunt connected between said cable and ground, said inductive shunt having magnetic material in its magnetic circuit, an electron discharge amplifier, a transformer coupling said amplifier to said shunt, and means to make the impedance of said receiving apparatus as viewed from said cable substantially higher for the component frequencies below the signaling frequency than for those above the signaling frequency.

12. In a submarine signaling system, a submarine cable loaded with magnetic material, signal receiving apparatus comprising an electron discharge amplifier and a transformer for coupling said amplifier to said cable, and means to make the impedance of said receiving apparatus as viewed from said cable substantially higher for the component frequencies below the signaling frequency than for those above the signaling frequency.

13. In a submarine signaling system, a submarine cable, a cable balancing return circuit, a receiving circuit comprising an inductive shunt connected between said cable and return circuit, and a signal indicating device connected to receive the voltage drop in at least a part of the inductance of said inductive shunt, and means to make the impedance of said receiving apparatus as viewed from said cable for all frequencies essential to signaling materially higher than the characteristic impedance of said cable and return circuit.

14. In a submarine signaling system, a submarine cable, a cable balancing return circuit, a receiving circuit comprising an inductive shunt connected between said cable and return circuit, and a signal indicating device associated with said inductive shunt, and means to make the impedance of said receiving apparatus as viewed from said cable for all frequencies essential to signaling materially higher than the characteristic im-

pedance of said cable and return circuit, and to make the impedance for component frequencies below the signaling frequency substantially higher than that for those above the signaling frequency.

15. A submarine cable loaded with nickel-iron alloy, and a receiving terminal network therefor which comprises resistance, capacity and inductance so proportioned that the impedance of the network measured from the cable is very high for the low frequency components of the signaling current.

16. A submarine cable loaded with nickel-iron alloy, and a receiving terminal network therefor which comprises resistance, capacity and inductance so proportioned that the lowest value of the impedance of the network measured from the cable is several times as high as the characteristic impedance of the cable for frequency components within the essential signaling frequency range.

17. A submarine cable loaded with nickel-iron alloy, and a receiving terminal network therefor which comprises resistance, capacity and inductance so proportioned that the lowest value of the impedance of the network measured from the cable is several times as high as the characteristic impedance of the cable for frequency components within the essential signaling frequency range and materially higher for the low frequency components of that range.

18. A submarine cable loaded with nickel-iron alloy, a receiving terminal network connected thereto, and a receiving instrument coupled to said network, said terminal network comprising resistance, capacity, inductance, and a signaling frequency transformer so proportioned that the impedance of the network measured from the cable is very high for the low frequency components of the signaling current.

19. A submarine cable loaded with nickel-iron alloy, a receiving terminal network connected thereto, and a receiving instrument coupled to said network, said terminal network comprising resistance, capacity, inductance, and a signaling frequency transformer so proportioned that the impedance of the network measured from the cable is at its lowest value several times as high as the impedance of the cable for frequency components within the essential signaling frequency range.

20. A submarine cable loaded with nickel-iron alloy, a receiving terminal network connected thereto, and a receiving instrument coupled to said network, said terminal network comprising resistance, capacity, inductance, and a signaling frequency transformer so proportioned that the impedance of the network measured from the cable is at its lowest value several times as high as the impedance of the cable for frequency components within the essential signaling frequency range.

- quency range, and materially higher for the low frequency components of that range.
21. A submarine cable loaded with nickel-iron alloy, a receiving terminal network connected thereto, and a receiving amplifier connected to said network, said terminal network comprising resistance, capacity, inductance, and a signaling frequency transformer so proportioned that the impedance of the network measured from the cable is, at its lowest value, several times as high as the impedance of the cable for frequency components within the essential signaling frequency range.
22. A submarine cable loaded with nickel-iron alloy, a receiving terminal network connected thereto, and a multi-stage electron discharge receiving amplifier having signal correcting networks between stages, said terminal network comprising resistance, capacity, inductance, and a signaling frequency transformer so proportioned that the impedance of the network measured from the cable is at its lowest value several times as high as the impedance of the cable for frequency components within the essential signaling frequency range.
23. A submarine cable loaded with nickel-iron alloy, a cable balancing return circuit, and a receiving terminal network therefor which comprises resistance, capacity, and inductance so proportioned that the impedance of the network measured from the cable is very high for the low frequency components of the signaling current.
24. A submarine cable loaded with nickel-iron alloy, a cable balancing return circuit, a receiving terminal network connected to said cable and return circuit, and a multi-
- stage electron discharge receiving amplifier having shaping networks between stages coupled to said terminal network; said terminal network comprising resistance, capacity, inductance, and a signaling frequency transformer so proportioned that the impedance of the network measured from the cable at its lowest value is several times as high as the impedance of the cable for frequency components within the essential signaling frequency range.
25. Terminal apparatus for a loaded cable, comprising a transformer and a network for connection between the transformer and the receiving end of the cable, said network being so designed that it tends to augment the effect of the cable in maintaining a steadily increasing electromotive force across the primary winding of the transformer as the result of the maintenance of a steady sending electromotive force at the sending end of the cable, the combined effect of the network and the cable being such that a substantially steady electromotive force appears across the secondary winding of said transformer for a period of the order of one second.
26. In a signaling system, a submarine cable loaded with magnetic material, a receiving terminal network therefor comprising resistance, capacity, and inductance so proportioned as to keep the magnitude of the received current below the value at which substantial hysteresis distortion of the signals is introduced.

In witness whereof, I hereunto subscribe my name this 16th day of August A. D., 1924.

AUSTEN M. CURTIS.
